UNITED STATES PATENT OFFICE.

JOHN J. TURNER, OF BATAVIA, NEW YORK, ASSIGNOR TO UNIVERSAL GYPSUM & LIME CO., OF CHICAGO, ILLINOIS, A CORPORATION OF DELAWARE.

CLAMPING MEANS FOR WALL BOARD OR THE LIKE.

Application filed December 29, 1923. Serial No. 683,529.

This invention relates to clamping means for vertically suspending panels of material on cars or trucks adapted to run on an overhead track in a drying kiln. It is concerned particularly with clamping mechanism for suspending in a vertical position wall board or panels in an undried state until the same is properly dried, such boards or panels having a plastic body which is of a weak or soft nature.

One of the objects of my invention is the provision of mechanism for hanging the panels on the car or truck so arranged that minimum obstruction will be offered to the free circulation of the air in the kiln between the suspended panels, and the efficiency of the kiln will be maintained at the maximum.

In clamping mechanism for the purpose stated, it is very desirable that the means by which the panels are suspended are of such construction that the panels are not marred or discolored. It has been found that wooden strips have little tendency to mar or discolor the panels. Since the strips must be securely clamped against the sides of the respective panels, there is no opportunity for the air to pass between the strips and the panels engaged thereby, consequently, those portions of the panels engaged by the strips are slow to dry. It is another object of my invention to provide clamping strips so constructed that the air may circulate freely through the strips, thus maintaining the strips in a relatively dry state so that they will more readily absorb the moisture from those portions of the panels engaged thereby.

The invention consists in the novel constructions and arrangements to be herein-after described and claimed for carrying out the above stated objects and such other objects as will appear from the following description of a certain preferred embodiment illustrated in the accompanying drawings, wherein—

Fig. 1 is a sectional view of a kiln equipped with mechanism embodying the principles of my invention;

Fig. 2 is a plan view, on an enlarged scale, of one of the clamping strips;

Fig. 3 is a side elevational view, also on an enlarged scale, of one of the clamping strips, certain portions thereof being broken out to show the internal construction; and

Fig. 4 is a perspective view, on a further enlarged scale, of a fragmentary portion of one of the strips.

Like characters of reference designate like parts in the several views.

Referring now to the drawings, it will be seen that the longitudinally extending kiln 8 is provided with an overhead track 9 on which a car 10 may be run. The car is preferably provided with two spaced cross members 11 from which the clamping mechanism is suspended.

The clamping strips 12 are preferably made of wood and are suspended at each end by inverted U-shaped clips 13 which are placed over the respective cross members 11 of the car. The ends of each clip are bent outwardly and are perforated for the insertion of bolts 14 which pass through the strips 12. The respective strips 12 are provided with a plurality of vertically extending passageways 15.

When the car is to be loaded, it is run out of the kiln. Some relatively stationary means is provided in association with the respective cross members 11 for the first panel 16 to be clamped against, said means in the present arrangement constituting the end clips 13^a and the clamping strip 12^a connected thereto, see Fig. 1, the nuts on the bolts connecting said clips and strip being turned on tightly, thus fixing the clips and strip securely to the members 11. The nuts on the bolts of all the other clips are not turned on tightly, the other clips, therefore, being slidable on the respective cross members 11. After the first panel 16 has been properly positioned with one of its sides bearing against the inner face of the clamping strip 12^a, the clips 13^b and the clamping strip 12^b attached thereto are moved over to bring one face of said clamping strip 12^b against the other side of said panel, said strip being temporarily and securely held in place by a set of suitable tools (not shown).

The panel 16^a is now placed with one of its sides bearing against the other face of the strip 12^b and then the clips 13^c and the clamping strip 12^c attached thereto are moved over to bring one face of said clamping strip 12^c against the other side of said panel 16^a, said strip 12^c being temporarily and securely held in place by another set of the tools mentioned above, which obviously will also serve to hold the strip 12^b and the

panel 16; whereupon the set of tools holding the strip 12^b may be removed. Likewise the other panels and strips are successively placed and held in position, the two sets of tools being alternately set and released. When the car has been loaded in this manner, the last strip 12^x is secured in place with one of its sides engaging the other side of the panel 16^w, which may be done in any one of several ways; in the present case, the nuts on the bolts fastening the clips 13^x to the strip 12^x are turned on tightly, thus fixing said strip and clips securely to the members 11.

15 The car with its load of suspended panels or boards is now run into the kiln. The vertically extending passageways 15 in the respective strips permit the air in the kiln to circulate freely between the panels. 20 There is no opportunity for air to become trapped between the panels under the respective clamping strips, as is the case when solid strips are used. Because of the better circulation of air in the kiln, the panels dry 25 in considerably less time than is the case when solid clamping strips are employed, and hence the efficiency of the kiln is materially increased.

Since the strips 12 are firmly clamped 30 against the sides of the panels, there is no opportunity for the air to circulate between the faces of the respective strips and those portions of the respective panels engaged thereby. Said portions of the panels are 35 usually the last to dry and are dried very largely by the respective clamping strips absorbing the moisture therefrom. By providing the passageways in the respective clamping strips so that the heated air in the 40 kiln may circulate freely through the strips, the strips themselves are maintained in a relatively dry state and, hence, those portions of the panels which are engaged by the strips are dried much quicker than is 45 the case when the strips are solid. I have also found, when the strips are constructed as described, that the tendency for them to warp is reduced to a minimum.

I do not intend to limit my invention to 50 the details of construction shown and described, except only in so far as certain of the appended claims are specifically so limited, as it will be obvious that modifications may be made without departing from the 55 principles of my invention.

I claim:

1. In mechanism of the class described, clamping and spacing means having oppositely disposed flat sides adapted to engage 60 the adjacent sides of panels of wall board or the like, said means having passageways so arranged that air circulating between the

panels may pass therethrough, for the purpose specified.

2. In mechanism of the class described, a 65 clamping or spacing strip of absorbent material and having oppositely disposed flat sides adapted to engage the adjacent sides of panels of wall board or the like, said strip having passageways so arranged that air 70 circulating between the panels may pass therethrough, for the purpose specified.

3. In mechanism of the class described, a wooden clamping or spacing strip, said strip having passageways so arranged that air 75 may circulate therethrough, for the purpose specified.

4. The combination with supporting mechanism, of a plurality of means adapted 80 to engage the sides of wall board or the like, said respective means having passageways so arranged that air may circulate therethrough, and means for attaching said respective first-named means to said supporting mechanism.

5. The combination with supporting mechanism, of a plurality of clamping or spacing strips adapted to engage the sides 85 of wall board or the like, said respective strips having passageways so arranged that air may circulate therethrough, and means for attaching said respective strips to said supporting mechanism.

6. The combination with supporting mechanism, of a plurality of wooden clamping or spacing strips adapted to engage the sides 90 of wall board or the like, said respective strips having passageways so arranged that air may circulate therethrough, and means for attaching said respective strips to 100 said supporting mechanism.

7. The combination with supporting mechanism, of a plurality of means having oppositely disposed flat sides adapted to engage 105 the respective sides of panels of wall board or the like, said respective means having passageways so arranged that air circulating between the panels may pass therethrough, and means for attaching said respective first-named means to said supporting mechanism.

8. The combination with supporting mechanism, of a plurality of clamping or spacing strips of absorbent material and having oppositely disposed flat sides adapted 115 to engage the respective sides of panels of wall board or the like, said respective strips having passageways so arranged that air circulating between the panels may pass therethrough, and means for attaching said respective strips to said supporting mechanism.

JOHN J. TURNER.
